UNITED STATES PATENT OFFICE

SAMUEL OLSON, OF OAK PARK, ILLINOIS, ASSIGNOR TO SAMUEL OLSON & COMPANY, INC., OF CHICAGO, ILLINOIS, A CORPORATION OF ILLINOIS

REFUSE CHUTE

Application filed May 5, 1927. Serial No. 188,909.

The purpose of this invention is to provide an improvement in refuse chutes having hoppers, the improved construction being designed to provide a closure for the hopper by 5 two doors so arranged that when one door is opened, the other will be closed, thus insuring an interruption of the direct passageway opening through the hopper to the chute at all times. It consists of certain elements 10 and features of construction shown and described, as indicated by the claims.

In the drawings:

Figure 1, is a vertical section taken through the hopper and chute, showing the two door arrangement forming the hopper closures; the dotted lines show the outer door or lid in different positions of opening.

Figure 2 is a transverse horizontal section through the chute and hopper, taken on line 20 2—2, Figure 1.

The two-door closure for the hopper is suitable for use in connection with refuse or rubbish chutes for tenement buildings and for manufacturing or commercial establishments. The arrangement embodied herein, prevents offensive odors from backing up the chute and entering the room, and also prevents dust and other small particles of refuse that usually float about the interior of the 30 chute, from being blown into the room by drafts in the chute. Further, this arrangement greatly reduces fire hazards, as chutes for refuse or rubbish are often directly connected to refuse burners from which small 35 burning particles may be given off and are blown up into the chute by reverse drafts but in this construction are positively kept out of the room by the double door arrangement.

40 In the drawings, a chute is indicated at 1, preferably constructed of fire resisting material, such as steel plate, capable of easy replacement and inexpensive. A hopper, 2, narrower than said chute, extends obliquely 45 upward from the front wall 3, of said chute and encloses a discharge opening, 4, formed in said front wall. The hopper is provided with an inner door, 5, and an outer door or lid, 6, forming closures for the discharge 50 opening, 4, from the hopper to the chute and

for the intake opening, 7, in the front upper end of said hopper, respectively. The outer door or lid, 6, is provided with a skirt, 8, secured to the under side thereof, at its outer edges and designed to fit snugly in the intake opening, 7, forming a substantially tight closure. The lid is hinged on said hopper for swinging upwardly, and has the edge thereof adjacent the chute, notched, the metal portions, 9, intermediate said notches being 60 rolled to form hinges. A portion of the front hopper wall, 3, near the discharge opening, 4, is bent at right angles to form a support, 10, for the hinged doors, 5 and 6. The plate support, 10, is also notched and the 65 portions, 11, intermediate the notches are rolled to form hinges for registering with the notches in the lid, 6, the hinges, 9, also registering with the notches of the support, 10. The hinge members thus formed are connected by a common pivot rod, 12, extending 70 transversely to permit the lid to swing about the pivot rod for opening. A spring catch, 13, of any suitable construction, preferably as shown, is secured to the front wall, 3, of the 75 chute for holding said lid in an upright position when open.

The inner door, 5, is of a width greater than the hopper, and its lateral edges abut against shoulders, 14, formed by offsetting 80 the side walls of the hopper adjacent the chute, thereby providing a substantial seat for the door. The door, 5, is of substantial weight and is hingedly supported at a point forward of the front wall of the chute so that the door will always hang out of plumb which gives it sufficient gravitational force to tend to close it. The upper edge of the door is notched with the intermediate portions, 15, 85 rolled to form hinges, as shown in Figure 1. These hinges register with spaces intermediate a number of hinge straps, 16, which are secured to the under side of the support, 10; said hinge straps also having registration 90 with the notches on the edge of said door. These hinge members are connected by a common pivot rod, 17, extending transversely across the chute, below the pivot rod, 12. An angle iron, 18, is secured to the door, 5, 100

adjacent its hinged connection on the side toward the hopper and is positioned so that a second angle iron, 19, which is attached to the under side of the lid, 6, will impinge upon it, thus providing a cam action to push door, 5, outwardly to uncover the discharge opening in the hopper. The engagement of these angles ceases when the lid is raised to the position indicated "A" in Figure 1, and the door, 5, again closes the discharge opening as indicated at "C" due to the door being out of plumb. The skirt, 8, of the lid, 6, maintains closure of the intake opening, 7, during the interval when the lid is being raised to position "A", and for the upward movement of the lid, 6, releases pressure of the angle irons against each other to permit the inner door, 5, to close the discharge opening, 4.

Although the inner door, 5, would normally close the discharge opening due to its offset hinged connection, as the lid is raised to open position "B", it is desirable to hold said door positively closed while filling the hopper with refuse, to prevent offensive odors, dirt, etc. from backing up in the chute and entering the room and to prevent sparks that may be floating about in the chute, from contacting with the rubbish in the hopper. Further, when this door is held in closed position, it permits the rubbish in the hopper to be packed or compressed without being forced into the chute, this applying especially to light weight refuse, as waste paper, packing materials, etc. To this end, I provide a flexible member shown as a chain, 20, one end being secured to the under side of the lid 6, and the other end attached to an adjustable eye bolt 21, secured in a clip fastened to the adjacent side of the door, 5, so that as the lid is raised to position "B" and held by the catch, this flexible member becomes taut and holds the door, 5, in closed position. As the lid is released and lowered to the position at "A", the impingement of the angle irons of the lid and door, forces said door outwardly to open the discharge opening of the hopper. It is essential that the door be positively opened, because light weight material may not provide adequate force to open said door even though it be packed fairly tight.

I claim:

1. In combination with a chute, a hopper connected thereto having an intake opening and an opening for discharge into said chute, a lid for the intake opening hinged to the hopper, a door for the discharge opening hingedly mounted and means disposed on adjacent sides of the lid and door dimensioned for impinging engagement as the lid approaches the final portion of its closing movement whereby the door is positively swung to open position when the lid is closed.

2. In combination with a chute, a hopper connected thereto having an intake opening

and an opening for discharge into the chute, a lid for said intake opening, a door for the discharge opening, and means operable during the final portion of closing movement of the lid for positively opening the door, said door being hingedly suspended and disposed out of plumb in closed position so as to automatically close the discharge opening upon release of the actuating means on the lid when the latter is opened.

3. In combination with a chute, a hopper connected thereto having an intake opening and an opening for discharge into the chute, a lid for said intake opening, a door for the discharge opening, and means operable during the final portion of closing movement of the lid for positively opening the door, said door being wider than the discharge opening and being hingedly suspended thereover, the sides of the hopper being flared out adjacent the chute to provide lateral abutments facing toward the chute for seating the door and the door being hung out of plumb so as to seat against said abutments by its own weight.

4. In the combination defined in claim 1, flexible means connecting the lid and door adapted to hold the door in closed position when the lid is fully opened.

5. In combination with a chute, a hopper connected thereto having an intake opening and an opening for discharge into the chute, a lid for said intake opening, a door for the discharge opening, and means operable during the final portion of closing movement of the lid for positively opening the door, said lid having a skirt engaging all the sides of the hopper in the intake opening from which it separates in its opening movement and dimensioned to keep said opening closed during that portion of the movement of the lid which actuates the door.

6. In the combination defined in claim 1, said door being adapted to close automatically and independently of the lid when the latter is raised sufficiently to separate the impinging means said lid having a skirt adjacent the sides of the hopper at the intake opening and adapted to keep the opening closed substantially until said impinging means are separated in the opening movement of the lid.

7. In combination with a chute, a hopper connected thereto having an intake opening and an opening for discharge into the chute, a lid for the intake opening arranged to seal said opening throughout a limited range of final closing movement, a door for the discharge opening, and means actuated by the lid during its limited range of closing movement for positively opening said door.

8. In combination with a chute, a hopper connected thereto having an intake opening and an opening for discharge into the chute, a lid for the intake opening arranged to seal

said opening throughout a limited range of initial opening movement, and means normally maintaining said door open when the lid is closed, said means being arranged to cause closure of the door during said limited range of opening movement of the lid.
